UNITED STATES PATENT OFFICE.

WILLIAM C. HEDGCOCK, OF ST. LOUIS, MISSOURI.

SIX-WHEEL TRUCK.

1,070,466.

Specification of Letters Patent. Patented Aug. 19, 1913.

Application filed January 30, 1913. Serial No. 745,146.

To all whom it may concern:

Be it known that I, WILLIAM C. HEDGCOCK, a citizen of the United States, residing at city of St. Louis, State of Missouri, have invented a certain new and useful Improvement in Six-Wheel Trucks, of which the following is a full, clear, and exact description, such as will enable others skilled in the art to which it appertains to make and use the same, reference being had to the accompanying drawings, forming part of this specification, in which—

Figure 1 is a partial plan view of my improved car truck. Fig. 2 is a side elevational view partly in section of said truck. Fig. 3 is a cross sectional view showing some of the parts in elevation.

This invention relates to a new and useful improvement in car trucks of the six wheel type, the object being to reduce the weight of the truck and to provide a simple, strong and economical structure which will fulfil all of the requirements of an equalizing six-wheel car truck.

It is well known that equalizing trucks are designed particularly to compensate for irregularities in the track, the load being distributed between the three pairs of wheels through the instrumentality of equalizing bars. It is the peculiar arrangement of these equalizing bars and the manner of mounting them in the truck side frame and the relation of said bars to each other and to the three pairs of wheels that form the essence of my present invention.

In the drawings 1 indicates the end axles on which are arranged the wheels 2.

3 is the middle axle on which is arranged the wheels 4. These axles and wheels may be of any ordinary and approved construction.

5 indicates a truck side frame preferably made of a casting and substantially channel or U-shape throughout the length of its upper member.

6 are pedestal jaws extending down from the central portion of casting 5 and in which is mounted a vertically guided journal box 7 in which the middle axle 3 is mounted. The casting is mounted and free to move up or down from the normal position shown in Fig. 2. The casting 5 is cut away immediately above the journal box 7 so as to permit the inner down-turned ends of the equalizing bars 8 to bear directly upon the journal box 7. These equalizing bars 8 are pivoted

at 9 at or near the outer and preferably upper ends of the journal side frame, said equalizing bars preferably lying partially within and partially without the channels of the side frame. In the drawing I have shown the outer ends of the equalizing bars as being provided with pedestal jaws 8^a but it will be readily understood that the journal boxes 10 which receive the ends of the axles 1 may be attached to the outer ends of the equalizer bars in any suitable or well known manner, or, if desired said boxes may be cast integral with said equalizer bars.

11 indicates column guides extending downwardly from the ends of the side frame, the lower ends of these column guides being connected by a spring bolster support which may be integral, as shown, or in the form of a removable piece, as desired. Where an integral spring support is used, the space between the column guides is widened at its lower portion to permit the introduction and removal of the bolster in the manner now commonly employed. The 70 spring support is provided with lugs 12 around which the bolster springs 13 are arranged, the lugs 12 centering said springs and preventing their displacement.

14 indicates the bolsters which may be of any ordinary or approved construction and which bolsters are connected by an X-shape casting 15 carrying the center plate 16. The ends of the X-shape member 15 may be attached to the bolsters in any suitable manner or, if desired, said member and the bolsters may be formed integral. The outer ends of the bolsters are also preferably connected by an arched bar 17, on which the side bearing may be carried.

In operation, it will be observed that the load is transmitted to the bolsters through the center plate or the side bearings on the bolster arched bars and that the bolsters in turn are supported by the bolster springs at the four corners of the truck. The springs in turn bear upon the ends of the side truck frames which side truck frames are pivotally supported on the pivot bolts 9 of the equalizing bars. The equalizing bars have their ends bearing upon (or carrying) the journal boxes in which the axles of the three pairs of wheels are mounted. As the middle set of journal boxes supports the inner ends of the oppositely extending equalizing bars, the pivotal point of said equalizers,—that is, the bolt 9, is located nearer the axle

boxes 10 than the boxes 7. In this manner the load is evenly distributed over the three sets of axle boxes, and, furthermore, the car body is yieldingly supported by the bolster spring. If desired, the X-shape frame carrying the center bearing could be suspended from stirrup hangers carried by the bolsters in a manner well known in swing motion trucks, or the said X-shape frame could be supported on rollers for the purpose of having limited lateral movement as is commonly employed in the well known Barber type of truck. The lower portions of the column guides 11 or the spring support connecting the lower portions thereof are preferably connected from one side of the truck to the other either by means of a tie-rod 18, as shown, or by means of a commercially rolled bar of any suitable cross sectional shape.

Having thus described my invention, what I claim is:

1. In a car truck, a side frame, an equalizing bar pivotally mounted upon said side frame and carrying a journal box at one end, the movement of which journal box and its axle being an arc about the pivotal point of the equalizer.

2. In a car truck, a truck side frame having a journal box capable of movement therein, an equalizing bar pivotally mounted upon said side frame in a horizontal plane above said journal box and having one end bearing upon said journal box, and another journal box carried by the opposite end of said equalizer bar the movement of said last mentioned journal box being in an arc of a circle about the pivotal point of the equalizing bar.

3. In a car truck, the combination of a truck side frame, a journal box slidably carried thereby at or about the center of said frame, equalizing bars pivotally mounted upon said frame in a horizontal plane above said journal box and having their ends bearing upon said journal box, and journal boxes carried by the outer ends of said equalizing bars, the movement of said journal boxes being in arcs of circles about the pivotal points of said equalizing bars.

4. In a car truck, the combination of a U-shape truck side frame, pedestal jaws connected thereto, a journal box slidably mounted between said pedestal jaws, equalizing bars arranged partially within the channel of said side frame and pivotally mounted at or near the ends thereof, and journal boxes carried near the outer ends of said equalizing bars.

5. In a car truck, the combination of a truck side frame having pedestal jaws and column guides, a journal box slidably

mounted in said pedestal jaws, bolsters yieldingly supported within said column guides, and equalizing bars pivotally mounted upon said side frame and carrying journal boxes at one end thereof.

6. A truck side frame substantially U-shape in cross section having pedestal jaws depending therefrom at about its middle portion, and a pair of column guides depending therefrom at each end.

7. A truck side frame substantially U-shape in cross section having pedestal jaws depending therefrom at about its middle portion, and a pair of column guides depending therefrom at each end, the space between each pair of column guides being widened at the lower portion thereof.

8. A truck side frame substantially U-shape in cross section having pedestal jaws depending therefrom at about its middle portion, and a pair of column guides depending therefrom at each end, each pair of column guides being connected at their lower ends, said connecting portions having lugs or teats having co-operation with the bolster springs.

9. In a six wheel truck, a side frame, two pairs of bolster guides formed integral therewith, and an integral member connecting the lower ends of each pair of bolster guides.

10. In a six wheel car truck, a side frame, two pairs of bolster guides formed integral therewith, and a horizontally disposed member connecting the lower ends of the members of each pair of bolster guides.

11. In a six wheel truck, a side frame, two pairs of bolster guides formed integral therewith, and bolster spring seats connecting the lower portions of said bolster guides.

12. In a six wheel truck, a pair of side frames, two pairs of bolster guides formed integral with and depending from each side frame, bolster spring supporting members integral with the lower ends of said bolster guides, and tie rods connecting the bolster spring supports from one side frame to the other.

13. In a car truck, a side frame comprising a top member, a pair of journal box pedestals formed integral therewith, two pairs of bolster guides formed integral therewith, and bolster spring supporting members uniting the lower ends of the bolster guides.

In testimony whereof I hereunto affix my signature in the presence of two witnesses, this 25th day of January, 1913.

WILLIAM C. HEDGCOCK.
